TREATMENT OF HYDROCARBON OILS

Valentine Mekler, Chicago, Ill., assignor to Universal Oil Products Company, Chicago, Ill., a corporation of South Dakota

Application February 3, 1932, Serial No. 590,548

2 Claims. (Cl. 196—67)

This invention relates to the treatment of hydrocarbon oils and refers more specifically to conversion of higher boiling hydrocarbons into lower boiling hydrocarbons of a more valuable character.

In one of its specific aspects the invention contemplates the provision of a process whereby hydrocarbon oils are cracked to produce high yields of low boiling hydrocarbons suitable for motor fuels possessing high anti-knock properties and of relatively low gum content permitting ready refining of the product.

In one of its specific embodiments the invention comprises subjecting hydrocarbon oils to cracking or conversion conditions of temperature by direct admixture therewith of hot combustion gases and subsequent further heating of the mixture by indirect contact with the hot combustion gases, which in turn are cooled prior to admixture with the hydrocarbons to be cracked. Thus, approximately 70 to 90 percent of the total heat required is applied by indirect means. The necessary time for the vapors at the cracking temperature to cause the desired conversion is allowed and thereafter the vapors are fractionated and condensed, collecting the low boiling product of the process and subjecting the reflux condensate from the fractionating zone to further cracking if desired. The gases may be treated in the usual manner for recovery of absorbed condensable low boiling hydrocarbons contained therein. Ordinarily in direct heating processes the gases of combustion must be cooled by admixing therewith a gaseous cooling agent prior to admixture with the hydrocarbon vapors, thus producing an abnormally high content of incondensable gases. The present process overcomes this objectionable feature.

It will be obvious from the following description that the present process possesses all of the advantages of the high temperature cracking processes wherein the hydrocarbons are heated by indirect means, such as high anti-knock product, but does not have the disadvantages of high gas losses and a product containing high gums; on the other hand, it possesses all of the advantages of processes wherein hydrocarbons are cracked by direct contact with hot combustion gases but does not have the disadvantages of diluting the hydrocarbons with excessive amounts of combustion gases which causes an increase in initial investment for larger equipment and larger operating costs.

Figure 1 of the attached diagrammatic drawings illustrates, in cross sectional elevation, a portion of a vapor-phase oil conversion process to which the principles of the present invention have been applied. Combustion chamber 1 is fired through one or a plurality of firing tunnels 2 to which fuel, in the form of oil, gas or pul-

verized solid fuel may be supplied through line 3 and valve 4 and introduced into the firing tunnel through a suitable burner, not shown, and enclosed within the end 5 of the firing tunnel. Air, steam or other atomizing and combustion supporting medium may be supplied to the burner through line 6, valve 7, line 8 and valve 9. The combustion chamber 1 is preferably a steel chamber, capable of withstanding super-atmospheric pressures, lined with suitable refractory material 12 indicated at 12. The combustion products may pass from combustion chamber 1 through duct 13 to mixing chamber 14.

Mixing chamber 14 preferably comprises an outer casing of steel, capable of withstanding super-atmospheric pressures, lined with suitable refractory material 12 and having concentric baffle walls 15 and 16 of any suitable material such as, for example, refractory shapes or high temperature metallic alloys; for example, silicon carbide. An inverted mixing cone 17 may be located within baffle 16, as illustrated in the drawings, hydrocarbon vapors being supplied to this zone through line 18 and valve 19. The combustion gases from combustion chamber 1 pass first downward in mixing zone 14 around baffle 15, thence passing upward within baffle 16 and coming into direct contact and commingling with the hydrocarbon vapors by means of a multiplicity of perforations 20 in mixing zone 17, serving to heat said hydrocarbon vapors by contact and direct admixture therewith. The mixture of hydrocarbon vapors and combustion gases may pass upward through the inner portion 21 of mixing zone 14, thence pass downward between baffles 15 and 16, being heated during their passage through this zone by indirect contact with the combustion gases prior to the admixture of said combustion gases with the hydrocarbon vapors and by radiation from the hot walls of the mixing chamber. The hydrocarbon vapors are thus heated to the desired conversion temperature, first by direct mixing with the partially cooled combustion gases and second, together with said admixed combustion gases which also serve to dilute the hydrocarbon vapors, by indirect contact with the relatively hot combustion gases and heating from radiating walls of the mixing chamber. The heated hydrocarbon vapors, together with the admixed combustion gases, may pass from mixing chamber 14 through duct 22 to reaction chamber 23. Reaction chamber 23 is also preferably constructed to withstand super-atmospheric pressures and, like zones 1 and 14, may be lined with suitable refractory material 12. The vapor-gas mixture may enter reaction chamber 23 at its lower portion passing upward around the inner zone 24, the walls 25 of which serve as a baffle directing the materials undergoing conversion first upward around their outer circum-

ference and then downward through zone 24 and out of the reaction chamber through duct 26.

Further treatment of the hydrocarbon combustion gas mixture such as fractionation, scrubbing, separation and final collection of the desirable products may be effected in well known forms of apparatus, not illustrated in the drawing, and not a specific part of the present invention.

Uncondensable hydrocarbon gases, together with combustion gases from the process and/or steam, or any inert gases, or combination of the above, may be recycled by a pump or compressor, not shown, through line 27 and valve 28 and may be supplied through line 29 and valve 30 into duct 13 and/or through line 31 and valve 32 into the outer portion of mixing chamber 14, serving as a means of diluting and increasing the volume of the combustion gases, reducing their temperature to the desired degree before they are added mixed with the hydrocarbon vapors. If desired, air or other combustion supporting medium may be diverted from line 8 through line 10 and valve 11 into line 29 to mix with said recirculated gases and effect combustion of hydrocarbon gases therein when introduced into the relatively hot mixing zone 14 or duct 13.

A preferred form of apparatus which combines the combustion and mixing zones in a single structure is illustrated diagrammatically in Figures 2 and 3 of the attached drawings. Figure 2 is a cross-section elevation of the apparatus and Figure 3 is a plan view of the same apparatus also shown partially in a section taken along line 3-3 in Figure 2. Referring now to Figures 2 and 3, the entire furnace is preferably encased in a steel shell 91 in order to permit the use of super-atmospheric pressures in the operation of the process, if so desired. This shell may be flanged at 92 and joined thereby with the upper head 93 of the heating and mixing unit which may comprise an upper mixing head 94 and lower header 95 and one or more concentric rows of tubes 96 which may be welded, rolled or otherwise joined at their upper ends to mixing head 94 and at their lower ends to header 95. Mixing head 94 may comprise concentric outer and inner walls 97 and 98 respectively, resembling an inverted U, when shown in cross-section, as in Figure 2, and provided with a multiplicity of perforations 99 through which the combustion gases may pass to mix with the hydrocarbon vapors in header 94.

The lower header 95, wherein the heated hydrocarbon vapors and admixed combustion gases collected after passage through the tubes 96, may be releasably joined, for example, by means of a slip joint arrangement, as indicated at 110, to the outlet line 111. It will be evident that by providing any desired form of joint of this general type, the entire heating and mixing unit may be removed from the furnace for cleaning or repairs simply by unbolting the flange joint 92 and lifting the heating and mixing unit from the furnace. This arrangement provides for expansion of the assembly upon heating. It will be understood that well known means, not illustrated, may be provided, if desired, for obtaining access to headers 94 and 95 and to tubes 96 without removing the unit from the furnace.

The walls 112 of the furnace may be constructed of any desired refractory material.

A central baffle 113, preferably of any suitable high temperature metallic alloy, may be joined to or formed integral with header 95 extending upward from this header to a point relatively

close to upper mixing head 94 and within the concentric row of tubes 96. An outer baffle 114 of the same or similar temperature resistant material, as baffle 113, may be provided outside the concentric rows of tubes 96 and may, if desired, be attached to the walls 112 of the furnace. If space is left between baffle 114 and walls 112, as illustrated in the drawings, vents 115 are preferably provided to allow for expansion of the gases within this space. Similarly a vent 116 may be provided in baffle 113. Additional perforations similar to 115 may be provided in baffle 114, the purpose of which will be more fully described later.

The furnace may be fired with any suitable fuel such as oil, gas or pulverized solid fuel introduced to burners 117 and 117' through lines 118 and 118' regulated by valves 119 and 119'. Air and/or steam may also be supplied to burners 117 and 117' through lines 120 and 120' regulated by valves 121 and 121'. As in Figure 1, a mixture of hydrocarbon gases and combustion gas from the process may be recirculated to the combustion and mixing zone through lines 124 and 124' controlled by valves 125 and 125', in which event the perforations 115, in baffle 114, serve as a means of distributing the recirculated gases to the combustion and mixing zone.

Steam or any inert gas may also, if desired, be supplied through lines 124 and 124', controlled respectively by valves 125 and 125', to the heating zone, serving as a means of diluting and increasing the volume of the combustion gases, reducing their temperature to the desired degree before they are admixed with the hydrocarbon vapors.

Also, as described in connection with Figure 1, air or other combustion supporting medium may, if desired, be mixed with the recirculated gases for the purpose of effecting combustion of the hydrocarbon gases in the mixture. This material may be supplied, for example, through lines 122 and 122' and valves 123 and 123'. It will be understood that, by variation of the size and location of perforations 115, the recirculated gases or other medium may be introduced at any desired point or points in the furnace.

The burners 117 and 117' supply the combustible materials to firing tunnels 126 and 126' and the ignited materials preferably enter the combustion zone 127 of the furnace tangentially in order to impart a turbulent and swirling motion to the combustion gases.

The combustion gases pass from combustion zone 127 upward around the tubes 96 through the restricted area between baffles 113 and 114. These relatively hot furnace gases, serving to heat the material passing through tubes 96, are somewhat cooled thereby and may pass into direct contact and admixture with hydrocarbon vapors introduced to mixing header 94 through port 128, said combustion gases being admitted preferably in the form of a multiplicity of finely divided streams through perforations 99 in header 94. The mixture of hydrocarbon vapors and combustion gases thence passes downward through tubes 96, being heated in their passage therethrough, by the relatively hot furnace gases, as already described. Heated materials from tubes 96 may be collected by means of header 95, passing therefrom through discharge line 111 to subsequent portions of the apparatus, not shown, for further treatment.

It will be understood that the apparatus illustrated in the drawings is only representative of some of the many types of heating equipment in

which the principles of the present invention may be utilized to advantage and therefore should not be construed as limitations upon the invention.

In order to compare the operating conditions 5 which may be employed and the results obtainable from the present improved process, as compared with cracking operations utilizing other heating means, we will first consider an operation representative of the conditions prevailing in 10 vapor-phase cracking processes in which direct heating is utilized exclusively, i. e., all of the heat is supplied to the hydrocarbon vapors to be treated by mixing them directly with hot combustion gases. Assuming a raw oil feed to the 15 system of 100 gallons per hour, a reflux ratio of 3, (i. e., 3 gallons of reflux condensate recycled to the system for retreatment, together with each gallon of raw oil charged) and assuming the weight of the combined feed (reflux and raw oil) to be 7½ pounds per gallon, a total of 3000 pounds per hour of oil vapors are to be treated. Assume 20 that the temperature of the vapors entering the mixing device is 850° F. and that the conversion temperature of the hydrocarbon-vapor combustion 25 mixture leaving the heating and mixing chamber is 1000° F. The total heat required will be approximately 445,000 B. t. u.'s per hour. Assuming that the combustion gases are mixed 30 with the hydrocarbon vapors at a temperature of 1800° F. and are cooled thereby to the outlet temperature by 1000° F., above mentioned, the available heat is approximately 265 B. t. u.'s per pound of combustion gas and the quantity of combustion gas required will be 1680 pounds per 35 hour. Assuming a super-atmospheric operating pressure of about 50 pounds per square inch, the total volume of combustion gases required at 1000° F., which is the approximate inlet temperature to the reaction chamber, and at the operating 40 pressure will be approximately 13,200 cubic feet per hour while the total volume of oil vapors under these same conditions will be approximately 3,300 cubic feet per hour. The volume of the mixture is therefore 16,500 cubic feet per hour 45 and the ratio of combustion gas to hydrocarbon vapor is approximately 4 to 1.

Considering now for the purpose of comparison an operation similar to the above except that the principles of the present invention are used; utilizing the same charging stock, assuming the same reflux ratio and the same total quantity of combined-feed (3000 pounds per hour), the same vapor inlet temperature (850° F.) to the heating and mixing device and the same conversion temperature (1000° F.), the temperature of the combustion gases mixed with the hydrocarbon vapors may be reduced to about 1200°-1400° F., and with the temperature of the furnace gases leaving the combustion zone at about 3700° F. the heat available, for both direct and indirect heating, is approximately 900-950 B. t. u.'s per pound. The quantity of combustion gases required is about 400-450 pounds per hour which, at 1200°-1400° F. and 50 pounds pressure, will occupy approximately 3200-3500 cubic feet. With the quantity of oil vapors remaining the same (3300 cubic feet) the total volume of the mixture under the operating conditions given will be approximately 6700 cubic feet per hour and the ratio of combustion gases to hydrocarbon vapors is only slightly greater than 1 to 1.

By comparison of the total volume of combustion-gas hydrocarbon-vapor mixture in the

two examples (16,500 cubic feet per hour by direct heating as compared with 6500-6800 cubic feet per hour by a combination of direct and indirect heating) it will be apparent that the capacity of a given apparatus may be increased nearly 2½ times by employing the principles of the present invention or, for a given capacity, a proportionately smaller apparatus may be utilized in the practice of the present invention.

An operation such as first described utilizing direct heating exclusively, may yield some 55% of motor fuel and approximately 12% of fuel oil, giving a total liquid recovery of about 67% based on the raw oil charged to the system, the remainder being uncondensable gas, coke and semi-solid polymerization products. The gasoline may be of high anti-knock value comparing, possibly, to an octane number of about 80.

The yields obtainable from an operation such as outlined in the second example, in which the features of the present invention are utilized, and employing gas oil as a charging stock, may yield 60% or thereabouts of motor fuel corresponding in antiknock value to an octane number of about 80 and in addition about 15% of marketable fuel 100 oil may be produced, the remaining products being principally uncondensable gas and a relatively small percentage of carbonaceous material.

The process is not limited in respect to the charging stock used and a wide range of operating 105 conditions may be employed. Hence the above examples are to be considered as illustrative and not as limitations upon the broad scope of the invention.

I claim as my invention:

1. In the vapor phase cracking of high boiling hydrocarbons for the production of lower boiling condensable products therefrom, the method which comprises mixing hydrocarbon vapors, free of liquid oil, with partially cooled combustion 115 gases, dividing the resultant liquid-free mixture into a plurality of parallelly flowing streams and passing the same in indirect heat-exchange with hotter combustion gases whereby the latter are cooled and the mixture heated, then utilizing the 120 last-mentioned gases as said partially cooled combustion gases, controlling the amount and temperature of the heating gases prior to said heat exchange to convert a substantial portion of the hydrocarbons into lower boiling condensable vapors without complete gasification of the hydrocarbons, and condensing and recovering as a product of the process the low boiling vapors thus 125 formed.

2. In the vapor phase cracking of high boiling hydrocarbons for the production of lower boiling 130 condensable products therefrom, the method which comprises mixing hydrocarbon vapors, free of liquid oil, with partially cooled combustion gases, dividing the resultant liquid-free mixture into a plurality of parallelly flowing streams and 135 passing the same countercurrent to and in indirect heat exchange with hotter combustion gases whereby the latter are cooled and the mixture heated, then utilizing the last-mentioned gases as said partially cooled combustion gases, controlling the amount and temperature of the heating gases prior to said heat exchange to convert a substantial portion of the hydrocarbons into lower boiling condensable vapors without complete 140 gasification of the hydrocarbons, and condensing and recovering as a product of the process the low 145 boiling vapors thus formed.

VALENTINE MEKLER.
